UNITED STATES PATENT OFFICE.

SAMUEL J. DUNKLEY, OF KALAMAZOO, MICHIGAN, ASSIGNOR TO DUNKLEY COMPANY, OF KALAMAZOO, MICHIGAN, A CORPORATION OF MICHIGAN.

PITTING-KNIFE.

1,370,098.

Specification of Letters Patent.

Patented Mar. 1, 1921.

Application filed January 28, 1919. Serial No. 273,599.

To all whom it may concern:

Be it known that I, SAMUEL J. DUNKLEY, a citizen of the United States, residing at Kalamazoo, in the county of Kalamazoo and State of Michigan, have invented certain new and useful Improvements in Pitting-Knives, of which the following is a specification.

This invention relates to improvements in pitting knives. It relates particularly to a development of my improved pitting knife described in my patent application filed January 11, 1917, Serial No. 141,888. This improvement is particularly in the head of the knife and in the means for oscillating the blade, the object being to provide a structure with larger clearance and greater strength and of great economy in production and easy renewal of the cutter blades or other parts.

Detailed objects and further objects as to economies of construction and operation will appear from the description to follow.

I accomplish the objects of my invention by the devices and means described in the following specification. The invention is clearly defined and pointed out in the claims.

A structure which is a preferred embodiment of my invention is clearly shown in the accompanying drawing, forming a part of this specification, in which—

Figure I is a side elevation view of full size of a pitter knife embodying the features of my invention.

Fig. II is a longitudinal sectional view showing details of construction, taken in the broken plane indicated by the section line 2—2 of Figs. III, IV, V and VI, the lower portion of the front half of the head being broken away to show details of construction and the driving shaft being shown in full lines.

Fig. III is a transverse detail enlarged sectional view taken on a line corresponding to line 3—3 of Fig. II.

Fig. IV is a transverse detail sectional view on line 4—4 of Fig. II.

Fig. V is a sectional view, somewhat enlarged, taken on line 5—5 of Figs. I and II.

Fig. VI is a detail edge elevation of the upper portion of the handle and head.

Fig. VII is an enlarged detail view of the serrated cutter.

55 In the drawing the sectional views are

taken looking in the direction of the little arrows at the ends of the section lines and similar numerals of reference refer to similar parts throughout the several views.

Considering the numbered parts of the drawing, 1 is a handle, preferably of aluminum. 2, 2 is the longitudinally divided head, the halves being symmetrical and extended into a screw-threaded shank 3 which is screwed into the bushing 4 within the handle 1. This bushing is of brass or bronze to give strength to the aluminum and provide a bearing for the shaft. The halves of the divided head are retained together by the screw 5 above.

Disposed in an arced guiding recess within the halves of this head is a curved oscillating segment 6 to which is secured a cutter 7 in the form of an arc of a circle, the ends being secured to the oscillating member 6 by screw 8, as clearly appears in Fig. II. The segment is disposed in the curved guideway 9. Within the transverse journal bearing opening 10, which is drilled through the lower end of the oscillating segment member 6 and opened out at the bottom thereof, is disposed a short cylinder or pin 3. This is slotted longitudinally and is capable of oscillation within the opening. The slot is disposed on the under side and is engaged by a wrist pin 11 which is carried on the end of the revoluble shaft 12. Shaft 12 is disposed within the bearings of the bushing 4.

Flexible shaft connections 14 and 15 are provided for the lower end of the handle 1, the outer shell 14 being secured to the handle and the tip 15 of the driving shaft being suitably engaged within the shaft 12 within the handle. These parts are driven by any suitable motor means or by a crank if desired. It is preferable that the shaft have a speed of revolution of about 1800 per minute.

In use the operator takes this tool in hand, and with the blade oscillating very rapidly, the same being suitably serrated on the edge, the pit of the peach or any other fruit is rapidly cut out. This is of special advantage in the pitting of cling-stone peaches, as the pit otherwise does not separate readily.

The blade 7 may be serrated on its edge as indicated by cross lines in Fig. 1 or may be left plain, and it may be beveled either

on the outside or the inside to facilitate its work, depending on the particular work in hand.

Having thus described my invention, what I claim as new and desire to secure by Letters Patent, is:

1. In a peach pitting knife, the combination of a handle, a longitudinally divided head, the divided lower end of which forms a screw threaded shank and the upper end of which is retained together by a screw, an arc-shaped guiding recess in the said head, an arc-shaped oscillating knife carrying segment within the said guide, a curved knife in the form of an arc of a circle, detachably secured to the said oscillating segment, a transverse journal bearing opening in the said oscillating member, a longitudinally slotted oscillating pin arranged in the said bearing member, a driving shaft axially disposed in said handle, and a wrist pin on the end of the said shaft disposed to engage the said slot and oscillate said knife, as specified.
2. In a peach pitting knife, the combination of a hollow handle with an axially disposed revoluble shaft therein, a longitudinally divided head, the divided lower end of which forms a screw threaded shank and the upper end of which is retained together by a screw, an arc-shaped guiding recess in the said head, an arc-shaped oscillating knife carrying segment within the said guide, a curved knife in the form of an arc of a circle, detachably secured to the said oscillating segment, and operative connections from said shaft to said oscillating member, coacting as specified.
3. In a peach pitting knife, the combina-

tion of a hollow handle with an axially disposed revoluble shaft therein, an arc-shaped guiding recess in the said head, an arc-shaped oscillating knife carrying segment within the said guide, a curved knife in the form of an arc of a circle, detachably secured to the said oscillating segment, a transverse journal bearing opening in the said oscillating member, a longitudinally slotted oscillating pin arranged in the said bearing member, a driving shaft axially disposed in said handle, and a wrist pin on the end of the said shaft disposed to engage the said slot and oscillate said knife, as specified.

4. In a peach pitting knife, the combination of a hollow handle with an axially disposed revoluble shaft therein, an arc-shaped guiding recess in the said head, an arc-shaped oscillating knife carrying segment within the said guide, a curved knife in the form of an arc of a circle, detachably secured to the said oscillating segment, and operative connections from said shaft to said oscillating member, coacting as specified.

5. In a peach pitting knife, the combination of a suitable handle, with a head therefor, a curved guideway in the said head, a corresponding oscillating member supported in said guide, a curved knife carried by said oscillating member, and actuating means supported by said handle for oscillating the said member and knife, as specified.

In witness whereof, I have hereunto set my hand and seal in the presence of two witnesses.

SAMUEL J. DUNKLEY. [L.S.]
